FIG. 1.

FIG. 2.

FIG. 4.

UNITED STATES PATENT OFFICE.

RUDOLPH HOFFMAN, OF CHICAGO, ILLINOIS, ASSIGNEE TO SEARS, ROEBUCK AND COMPANY, OF CHICAGO, ILLINOIS, A CORPORATION OF NEW YORK.

BLUE-FLAME OIL-BURNER.

1,092,262.

Specification of Letters Patent.

Patented Apr. 7, 1914.

Application filed August 8, 1913. Serial No. 783,843.

To all whom it may concern:

Be it known that I, RUDOLPH HOFFMAN, a citizen of the United States, residing at Chicago, in the county of Cook and State of Illinois, have invented certain new and useful Improvements in Blue-Flame Oil-Burners, of which the following is a specification.

This invention relates to burners for burning kerosene and other hydrocarbon oils to produce what is known as a blue flame.

The invention is herein shown as embodied in a burner which is especially adapted for use in a cook stove.

In the accompanying drawings, Figure 1 is a perspective view of a device embodying the features of my invention. Fig. 2 is a vertical central sectional view of the burner and the chimney. Figs. 3 and 4 are views illustrating a means for detachably connecting certain parts of the burner. Fig. 5 is a fragmental sectional view of the burner on a larger scale than that of Fig. 2. Fig. 6 is a fragmental sectional view of the wick tubes and the means for supporting the inner air controller.

The body 1 of the burner comprises an inner wick tube 2 and an outer wick tube 3 connected together at their lower ends so as to form a tubular receptacle for the wick 4 and a quantity of oil. The body may be connected to the oil reservoir by any preferred means, and may be mounted in the framework of the stove in any common or suitable manner. In the construction herein illustrated, the outer wick tube terminates in a horizontal plane slightly below the plane of the top of the inner wick tube, and the upper end of the outer wick tube is preferably bent inwardly slightly, as shown. Air is admitted to the inner and outer sides of the annular flame produced by the wick, the air being controlled by an inner air controller and an outer air controller. The form of inner air controller 5 which has been selected for illustration is of generally frusto-conical form, the larger upper end of the controller being located approximately in the plane of the upper end of the inner wick tube. Above the plane of the largest diameter of the inner air controller is an annular flange 6 which first extends inwardly and upwardly and then outwardly. 7 is a disk which extends transversely of the inner air controller in the plane of the largest diameter of said controller.

While the inner air controller may be supported in various ways, it is herein shown as loosely supported concentrically with the wick tubes upon a cupped member or ring 8, said ring being supported within the body 1 by means of a spider 9. Said spider may, if desired, be formed of two sheet-metal cross-bars intersecting each other at right angles, the ends of said bars being secured to the inner wick tube by means of solder or in any other suitable manner.

The ring 8 has an outwardly extending annular flange 8^a which causes the air current to flow upwardly close to the inner wick tube, said air current carrying up any vapors which might otherwise flow down the inner wick tube and condense on said tube.

The outer air controller is of annular form and in the present embodiment consists of an inner section 10 which is mounted upon and rigidly secured to the outer wick tube, and an outer section 11 which is detachably mounted upon the section 10.

The inner section 10 of the outer air controller comprises an annular horizontal flange 12 having perforations 13 or the like therein, and a vertical annular flange 14 having locking projections 15 upon its upper edge. Each of these projections comprises a locking shoulder 16 and two oppositely-inclined surfaces 17 and 18.

The outer section 11 of the outer air controller comprises an annular ring 19 having a shoulder 20 to support the chimney 21. Attached to the lower portion of the ring 19 is an annular flange 22 having perforations 23 therein. At the inner edge of the flange 22 is a downwardly and outwardly inclined imperforate flange 24 adapted to rest upon the flange 12. In the flange 22 is a plurality of slots 25, one for each of the locking projections 15. At the inner edge of the flange 22 is an upwardly extending annular flange 26 encircling the outer wick tube and spaced a short distance therefrom in order to provide a restricted air passage 26^a between the outer wick tube and said flange. The lower end of said passage communicates with the atmosphere through the perforations 13. In order to restrict the flow of air upwardly through said passage, there may be placed in said passage, as herein shown, a ring 27 having corrugations ex-

tending vertically thereof. The air current in the passage 26^a prevents vapor from flowing down the outer wick tube and condensing. The upper end of the annular flange 26 is preferably flared outwardly, as shown, and extends above the horizontal plane of the top of the inner wick tube. The outer section 11 of the outer air controller further comprises two inwardly extending flanges 28 and 29 which are connected to the ring 19. The inner portions of the flanges 28 and 29 are above the wick tubes and terminate approximately midway between the wick tubes. These flanges form between them an air passage 30 through which air is directed in a downwardly inclined sheet against the flame. Air is admitted to said passage through perforations 31 in the flange 29. Air is admitted to the flame through the space 32 between the flange 29 and the upper outwardly-flared portion of the flange 26 through the perforations 23 and 33 in the flange 22. The outwardly flared edge of the ring 26 protects the base of the flame from the relatively strong current flowing through the space 32.

The chimney 21 may be provided with a suitable window 34. When the burner is to be lighted, the operator opens the window 34 and applies a match to the wick. In order to facilitate the ignition of the wick, the inner air controller 5 may, if desired, be tilted upon its seat 8. The amount of air supplied through the passages 26^a, 30 and 32 and the space between the inner wick tube and the inner air controller 5 is such that a blue flame is produced.

When it is desired to trim or replace the wick 4 the outer section 11 of the outer air controller is turned until the flange 22 is clear of the locking surfaces 16, the section 11 being then lifted off the wick tubes. After the wick has been trimmed or renewed, the section 11 is replaced, the inclined surfaces 17 and 18 guiding the flange 22 onto the locking projections 15. When the flange 24 rests upon the flange 12, the section 11 is turned by the operator in the direction to carry a portion of the flange 22 beneath each of the locking shoulders 16.

While I have described the present embodiment of my invention with considerable particularity, I would have it understood that the invention is not limited to the precise arrangement of parts herein disclosed, but that various modifications may be made by those skilled in the art without departing from the spirit and scope of the invention as set forth in the appended claims.

60 I claim as my invention:

1. In a blue-flame oil burner, the combination of inner and outer wick tubes; means for controlling the supply of air to the inner side of the flame; and means for controlling the supply of air to the outer side of the

flame, the last mentioned means comprising an annular vertical flange surrounding and spaced from the outer wick tube and forming a restricted air passage, said flange extending above the wick tube and having its upper portion flared outwardly, and two inwardly extending flanges, one above the other, and both located above the first mentioned flange for directing a sheet of air downwardly against the outer side of the

70

2. In a blue-flame oil burner, the combination of inner and outer wick tubes; means for controlling the supply of air to the inner side of the flame; and means for controlling the supply of air to the outer side of the flame, the last mentioned means comprising an inner and an outer section, the inner section comprising a perforated flange fixed to the outer wick tube, and the outer section resting upon said flange and being detachably connected to the inner section, said outer section comprising means for supplying a limited amount of air to the base of the flame, the air so supplied entering through the perforations in said flange, and means thereabove for directing a sheet of air against the outer side of the flame.

90

3. In a blue-flame oil burner, the combination of inner and outer wick tubes; means for controlling the supply of air to the inner side of the flame; and means for controlling the supply of air to the outer side of the flame, the last mentioned means comprising an inner and an outer section, the inner section comprising a horizontal perforated flange secured to the outer wick tube and a vertical flange having a locking projection provided with a shoulder, and the outer section comprising means for supplying a limited amount of air to the base of the flame, and means thereabove for directing a sheet of air against the outer side of the flame, said outer section comprising a flange having a slot adapted to receive said locking projection, said outer section being adapted to be rotated to carry said flange beneath the shoulder of said locking projection.

105

110

4. In a blue-flame oil burner, the combination of inner and outer wick tubes; means for controlling the supply of air to the inner side of the flame; and means for controlling the supply of air to the outer side of the flame, the last mentioned means comprising an annular ring encircling the outer wick tube, a perforated annular flange, means cooperating with said flange to support said ring, two annular flanges extending inwardly from said ring to a point above the wick tubes and adapted to direct a sheet of air against the outer side of the flame, and means for supplying a limited amount of air to the base of the flame.

115

120

125

5. In a blue-flame oil burner, the combination of inner and outer wick tubes; means

130

for controlling the supply of air to the inner side of the flame; and means for controlling the supply of air to the outer side of the flame, the last mentioned means comprising an outwardly extending flange secured to the outer wick tube, said flange having a vertical portion, a locking projection on said vertical portion, said projection being provided with a shoulder, said 5 outer section comprising a flange having a slot adapted to receive said locking projection, said outer section comprising a flange arranged to rest upon said outwardly extending flange and having a slot adapted to receive said locking projection, said outer section being adapted to be rotated to carry the slotted flange beneath the shoulder of said locking projection.

6. In a blue-flame oil burner, the combination of inner and outer wick tubes; a frusto-conical member supported with its portion of greatest diameter located substantially in the plane of the tops of the wick tubes, and having an inwardly and upwardly inclined flange above said portion of greatest diameter, and means located in the horizontal plane of said flange for directing a sheet of air against the outer side of the flame, whereby the flame is caused to converge inwardly above said portion of greatest diameter.

7. In a blue-flame oil burner, the combination of inner and outer wick tubes; means for controlling the supply of air to the outer side of the flame; a frusto-conical member for controlling the supply of air to the inner side of the flame, the portion of largest diameter of said member being substantially in the plane of the top of the wick tubes; and a cupped member rigidly secured to the inner wick tube in which the smaller end of said frusto-conical member is loosely and removably seated.

8. In a blue-flame oil burner, the combination of inner and outer wick tubes; means for controlling the supply of air to the inner side of the flame; and means for controlling the supply of air to the outer side of the flame, the last mentioned means comprising a vertical flange encircling the outer wick tube and spaced relatively close thereto so as to form a restricted air passage, a vertically corrugated ring in said air passage; and means for directing a sheet of air against the outer side of the flame.

9. In a blue-flame oil burner, the combination of inner and outer wick tubes; means for controlling the supply of air to the outer side of the flame; a frusto-conical member for controlling the supply of air to the inner side of the flame, the portion of said

member of greatest diameter being approximately in the horizontal plane of the tops of the wick tubes; a seat within the inner wick tube on which the lower, smaller end 65 of said member is supported; and an annular flange adjacent to the lower end of said member for confining the air current to a position close to the inner wick tube.

10. In a blue-flame oil burner, the combination of inner and outer wick tubes; means for controlling the supply of air to the inner side of the flame; and means for controlling the supply of air to the outer side of the flame, the last mentioned means including an annular ring encircling the outer wick tube, a perforated annular flange extending inwardly from said ring, an annular perforated flange extending outwardly from and secured to the outer wick tube, 70 said inwardly extending flange being removably supported upon said outwardly extending flange, an annular flange extending upwardly from the inner portion of said inwardly extending flange and forming 75 a restricted air passage around the outer wick tube, air being admitted to said passage through the perforations in said outwardly extending flange, and means above said upwardly extending flange for directing 80 a sheet of air against the outer side of the flame.

11. In a blue-flame oil burner, the combination of inner and outer wick tubes; means for controlling the supply of air to the inner side of the flame; a flange extending outwardly from the outer wick tube; a vertically extending ring having near its lower edge an inwardly extending flange which is removably supported on the first flange, the 95 second flange being perforated; a perforated flange attached to and extending inwardly from the ring and above the wick tubes; an imperforate flange attached to and extending inward from the ring above the 100 third flange, said imperforate flange and third flange forming means to direct a sheet of air against the outer side of the flame; an annular flange extending upwardly from the inner portion of the second flange and forming 105 a restricted air passage around the outer wick tube, the upper portion of said upwardly extending flange being flared and extending above the wick tubes and forming with the third flange an air passage.

In witness whereof I affix my signature in presence of two witnesses.

RUDOLPH HOFFMAN.
